UNITED STATES PATENT OFFICE

ADOLF ENSSLIN, OF NORTH ATTLEBORO, MASSACHUSETTS

TUMBLING MACHINE

Application filed September 29, 1928. Serial No. 309,285.

My invention relates to machines wherein a rotary receptacle containing shot or other abrasive elements are employed for polishing articles of various shapes.

Heretofore barrels or like receptacles have been used for this purpose with little or no success upon articles having extended plane areas, such as plates or disks, both because the substantially circular transverse curvature of the barrel caused the articles to bridge large areas of the barrel, thus excluding the abrading elements from one side of the plate and wasting space, and because articles having flat surfaces, adhered to the barrel ends. This was true regardless of whether the interior of the barrel was ribbed or grooved.

One essential object of my invention is to overcome the deficiencies above set forth.

Other essential objects are to prevent fracture of the receptacle; to insure that any interruption of the rotation of the receptacle shall occur only when the portion thereof containing the supply orifice is uppermost, to lock the receptacle against assuming a position wherein the orifice is either uppermost or lowermost; and to afford a convenient, easily operable, and tight closure adapted to eliminate strain upon the receptacle.

Other objects and advantages will be apparent to those skilled in the art from an inspection of the specification herein.

To the above ends primarily my invention consists in such parts and in such combinations of parts as fall within the scope of the appended claims.

In the accompanying drawings which form a part of this specification,

Figures 1, 2, and 3, are a top plan view, a front elevation, and an end elevation respectively of a tumbling machine embodying my invention,

Figure 4, a transverse section on line 4—4 of Figure 1,

Figure 4^a, a section on line 4^a—4^a of Figure 4,

Figure 5, a longitudinal section of the receptacle,

Figure 5^a, a fragmentary elevation of a portion of the cover viewed in the direction 50 of the arrow shown in Figure 5,

Figure 6, a fragmentary front elevation of the machine partially in vertical central section,

Figures 7 and 8, transverse sections taken on line 7—7 of Figure 6, showing the lever in engaged and disengaged positions respectively,

Figure 9, a section taken on line 9—9 of Figure 1 showing the locking bail in unlocked position,

Figures 10 and 11, sections taken on line 10—10 of Figure 2 showing the bail in locked and unlocked positions respectively, and

Figure 12, a section taken on line 12—12 of Figure 10.

Like reference characters indicate like parts throughout the views.

As herein illustrated the frame of my machine includes a base 18 comprising a front portion 19 and a rearwardly extending end portion 20. The top of the former is provided with an inclined portion 21. Screwed or otherwise fixed to the front portion of the base are a plurality of standards or supports 22 and 23, in this case two in number. The standard 22 is provided with bearings 24 and 25, and the standard 23 with a bearing 26, the former two bearings for a driven shaft 28, and the latter for a trunnion 29. Screwed to the portion 20 of the base are standards or supports 30 having bearings 31 for a driving shaft 33 fast to which is a pulley 35 actuated from any convenient source of power. A sprocket chain 37 engages a sprocket wheel 38 fixed to the driving shaft and a similar wheel 39 fast to an intermediate or main shaft 40, whereby the latter is driven. A sprocket wheel 44 also fixed to the shaft 40 rotates the driven shaft 28 through connections hereinafter set forth.

A carrier 46 for the tumbling receptacle 47 includes a rectangular frame 48 having flat ends 49 and flat sides 50 integral with the latter. The ends have each a longitudinally disposed inwardly directed abutment portion 51. Centrally of the frame ends 49 and extending through the abutment portions are openings 52 see Figure 5 in alignment with which are outwardly directed collars or hubs 53 integral with the ends. The hubs are fixed by

screws 55 or otherwise to the shaft 28 and to the trunnion 29. The upper and lower faces of each abutment portion is provided with a longitudinal groove 57 forming in each case a vertical shoulder 58. Attached to the upper and lower portions of the frame end portions 51 are upper and lower substantially segmental plates 60 and 61 respectively, all provided with inwardly directed undulating peripheral flanges 63. Each of the upper and lower plates has integral with its plane edge, throughout the length thereof, an offset angular flange 65 comprising an outwardly directed horizontal portion 66 and a terminal portion 67 disposed at right angles to the portion 66. The flange portions 67 of the upper plates 60 are downwardly directed and rest in the upper grooves 57 and abut against the adjacent shoulders 58, while the flange portions 66 thereof are slightly spaced from the shouldered or elevated portions 58 of the abutment portions 51. The flange portions 67 are slightly narrower than the width of the grooves 57, as at 68. The flange portions 67 of the lower plates 61 are upwardly directed and register in the lower grooves 57 and abut against the lower shoulders 58. The plates 61 are rigidly attached to the ends of the frame by a plurality of screws 69 engaging in threaded holes 71 in the lower flange portions 66 and in threaded cavities 72 in the lower abutment portions 51 of the frame ends. The upper plates 60 are attached to the frame ends as follows. A plurality of tensioned binding screws 75 have heads 76 and extended shanks 77. The latter engage in holes 79 of the upper flange portions 66 and in threaded cavities 80 in the upper abutment portions 51 of the frame ends. A helical spring 81 surrounds the shank of each screw 75 with its lower end resting on the flange portion 66, and its upper end abutting the screw head.

The receptacle 47 is hollow and is embraced by the flanges 63 of the end plates 60 and 61. It is composed entirely of glass and in detail comprises an undulatory body portion 83 comprising annularly arranged longitudinally disposed waves or undulations 84. Its end portions 85 are also undulatory comprising radially disposed flaring undulations 86. Intermediate its length the top of the body portion of the receptacle is provided with a mouth or opening 87 formed by a projecting annular neck or flange portion 88 provided with a bead 89.

A closure or cover 90 for the mouth 87 comprises a circular base plate 92 provided in its under side with an annular recess 93 for the reception of a gasket 94 adapted to rest upon the neck 88, and held by the overlapping margin of a retaining plate 95 fixed by screws 96 to the plate 92. Integral with the top of the latter is a rectangular housing block 97 see Figure 3 provided with a cen-

tral bore 98 and with four radial slots 99 enlarged at intermediate points to form vertically disposed cavities 100. The slots 99 are continuous with slots 101 which bifurcate radially extending wings 102 integral with the block forming pairs of parallel guide walls 103. Upon the outer ends of the walls are vertically disposed laterally extending guide flanges 104 integral with the periphery of the base plate 92 forming guideways continuous with the guideways formed by the wing walls 103. Rocking levers 106 are pivoted intermediate their lengths upon pins 107 in each pair of guide walls 103. The levers have reduced inner end portions 108 extending into the bore 98 of the block 97, and reduced outer ends 109 projecting through holes 110 in vertically slidable plates 111 mounted in the guide flanges 104. Near their lower ends are horizontal slots 112 forming hooks 113. An operating screw 115 has an unthreaded portion received in an opening 116 in a retaining plate 117 fixed to the top of the block 97 by screws 118. The operating screw has a head 120, an enlarged intermediate portion 121 and a reduced lower portion 122 provided respectively with threads 123 and 124 of different pitches. Upon the screw portion 121 is mounted a nut 126 whose thread corresponds in pitch with the thread 123. A nut 128 on the screw portion 122 has a thread corresponding in pitch with the thread 124. The nuts 126 and 128 have each four radial fins 129 and 130 respectively slidable in the slots 99 of the block. Helical springs 132 in the cavities 100 enclose the lower ends of guide pins 134 slidable in vertical holes 135 in enlarged portions 137 of the nut wings 129 see Figure 4^a, and the tops of the springs abut against the bottoms of the enlarged portions while the headed lower ends 139 of the pins 134 rest upon the ends 108 of the levers which in turn rest upon the fins or wings 130 of the nut 128. A hand lever 141 is fixed in the head 120 of the operating screw 115, and a washer 143 upon the upper portion of the screw abuts against the retaining plate. A band 145 embracing the neck 88 of the receptacle is clamped thereon by means of a tightening screw 146 connecting end lugs 147 upon the band. Four screws or pins 148 spaced a quarter circumference upon the band are adapted to be slidably received in the hook portions 113 of the vertical plates 111.

The means for actuating the shaft 28, which carries the receptacle, includes a sprocket chain 150 which engages the sprocket wheel 44 on the shaft 40, and a like wheel 151 whose hub portion 152 is free on the shaft 28 and is provided in its operative face with a radial slot 153. Adjacent this member upon the shaft 28 is the slideable sleeve 154 of a clutch device provided in one end face with an inclined cam shoulder 156 and with a

flat radial lug 157 adapted to register in the slot 153, but of as much greater length than the depth of the slot as to equal the height of the cam shoulder 156. The opposite end 5 of the sleeve 154 is provided with a diametrical slot 159 and with a cavity 160. The non-slidable member of the clutch device includes a collar 162 provided upon one end face with a cavity 164, and with lugs 165 adapted to 10 slidably enter the slot 159. A guide pin 167 is surrounded by a helical spring 168 having its ends seated in the cavities 160 and 164. The collar, 162, located beside the bearing 24, has an internal thread 169 engaging an external 15 thread 170 upon a reduced end portion 171 of a second collar 172 of which it is a constituent part. The collar 172 is loose in both the bearing 24 and upon the shaft 28 which has an end portion 174 of enlarged diameter 20 rotatable in the central bore 176 of a locking head 177 upon the collar 172 abutting against the outer end of the bearing 24 and extending therefrom. The head 177 is transversely U shaped and its upper and side portions 25 are cut away to form an arched recess 179. Extending transversely through the lower portion of the head is a cylindrical bore 181 which is in alignment with a transverse peripheral semicylindrical groove 182 in the 30 enlarged portion 174 of the shaft 28 when the latter has reached a certain point in its rotation. If the peripheral portion of the shaft 28 closest to the receptacle mouth 87 be regarded as the top of the shaft, the groove 35 182 is upon the bottom of the shaft. Rotatably mounted in the bore 181 is a cylindrical locking pin 183 with a central longitudinally disposed arcuate recess 184 in its periphery. Fast to the outer ends of the pin is a bail 186 40 which is, in this instance, assisted in maintaining either an upright or a depending position, as shown in Figure 12, by a pin 188 slidable in a recess 189 in the member 183 and pressed by a spring 191 therein to register 45 with diametrically oppositely disposed cavities 192 and 193 in the head 177. It will be observed that when the bail 186 is manually raised to position shown in Figures 10 and 6 the solid portion of the pin 183 is in the cavity 50 182, and the shaft 28 is thus interlocked with the collars 172 and 162, which is normal running position; but when the bail is in the depending position shown in Figures 9 and 11, the recess 184 is presented to the enlarged 55 portion 174 of the shaft 28, so that the latter rotates freely without moving the sleeves. In the clutch operation the spring 168 forces the lug 157 of the sleeve 154 into the slot 153 of the hub 152 of the sprocket wheel 151, as 60 shown in Figure 6, which is the running position of the machine, wherein the chain 150 from the sprocket 44 on the shaft 40 drives the shaft 28 through the inter-engaged members 152, 154, 162, 172, and 183. 65 When, however, it is desired to interrupt the rotation of the shaft 28 the following means is employed. As shown in Figures 7 and 8, a flat upright lever 196 having a flat upper end is pivoted intermediate its length upon a pin 198 in intermediate portions of vertical parallel lugs 199 projecting from 70 the front of the standard 22. This lever has its lower portion beveled as at 200. A second or auxiliary flat lever 201 slidably engages the lever 196 and is likewise pivoted intermediate its ends upon the pin 198, and has its lower portion beveled, as at 202. It is provided near its top with a rectangular lateral recess 203 at a point above the end 75 of the lever 196 whereby is formed a hook or beak 204 above the first lever and parallel with its top edge. A stop pin 206 in the upper portion of the lever 201 bears against the front edge of the lever 196. Integral with the standard 22 is a rearwardly directed boss or 80 extension 208 provided with horizontal bores 210 and 211 spaced from each other and extending to the front face of the standard. Reduced portions 212 and 213 of these bores respectively extend to the rear face of the boss. A plunger 214 in the bore 210 has a head 215 pressed against the lower portion of the lever 196 by a helical spring 216 having one end abutting against the head and its other end abutting against a shoulder 217 formed by the bore portions. A plunger 218 in the bore 211 engages with its forward end the lower portion of the arm 201 and is forwardly pressed by an expansion spring 220 having its front end fixed to an intermediate 90 portion of the plunger, and its other end abutting against the internal shoulder 222. The levers are controlled by a hand lever comprising a handle arm 224 and an angular cam 225 pivoted on a pin 226 in the lower portions of the lugs 199. In this instance a web 228 connecting the lower ends of the lugs 199 forms a rest for the hand lever. The lower front edge of the lever 196 is maintained in contact with the cam 225 by the 95 plunger 214; and the pin 206 of the lever 201 is pressed against the lever 196 by plunger 218. When one cam face, 230, is engaged by the lever 196 the latter is in inactive position, as shown in Figure 7. When the second cam face 231 is engaged by the lever 196, as 100 shown in Figure 8, the latter is in operating position. That is to say when the lever arm 224 is manually depressed the spring 216 is permitted to force the upper portion of the lever 196 into the path of the cam shoulder 156 upon the clutch member 154, whereby the latter is forced towards the member 162, thus 105 withdrawing the lug 157 from its seat 153, and throwing out the clutch and stopping the 110 machine. As the clutch controlling arm 196 is impelled into engagement as described, the lever 201 advances therewith bringing the hook 204 into the path of the lug 157 so that 115 the beak 204 snaps over the lug and cooper- 120 125 130

ates with the top of the lever 196, as shown in Figure 7, to hold the lug in horizontal position, whereby the mouth of the receptacle 87 stops and remains stationary in its uppermost position.

In operating my device the cover 90, which is shown in clamped and unclamped positions respectively in Figures 1 and 5, is removed. This is effected by turning down the screw 115 by the hand lever 141 whereby the pressure of the springs 132 upon the clamping levers 106 is lessened, and the upward tension of the clamping plate hooks 113 upon the pins 148 thereby relieved. The cover 89 is now manually turned slightly to disengage the pins from the hooks. Since the receptacle neck is of glass the yielding character of the clamping means prevents accidental fracture of the former.

After the removal of the cover 90 the abrasive elements and the plates or other articles to be treated thereby are introduced into the receptacle through the mouth 87, the receptacle being maintained in upright position for this purpose by the engagement of the levers 196 and 201 with the clutch lug 157. The cover is next replaced.

The lever handle 224 is next manually elevated to free the clutch and permit the rotation of the receptacle and shaft 28 from the pulley 35, chain 37, shaft 40, chain 150 and the described clutch connections.

When it is desired to dump the receptacle the lever handle 224 is pressed, and the rotation of the receptacle stopped and the cover may be removed, but, by reason of the engagement of the locking lever 201 with the clutch lug 157, the mouth of the receptacle is in upright position. To obviate this difficulty the bail 186 of the locking pin 183 is manually turned from its upright to its depending position which permits the shaft 286 to rotate freely and independently of the clutch elements and their connections. Thus the receptacle may be manually and by gravity turned or reversed and the contents thereof be withdrawn or be dumped upon the inclined portion 21 of the base portion 19.

The main shaft 40 may be extended in length by couplings to any extent convenient for transmitting power to a gang or plurality of the described machines.

It will be observed that by virtue of the undulatory character of both the body portion and ends of the tubing receptacle that flat articles may be polished on both sides, because their flat faces cannot anywhere find any corresponding flat area upon the receptacle to which to adhere. Also large flat articles may be herein treated because the undulatory form of the receptacle compels tilting of the article.

The character of the framework carrying the receptacle is such as to permit the latter to be constructed of glass; since, among other

things the upper retaining plates 60 are engaged to the adjacent frame portions by clamping screws cushioned by springs 81. The nonrigid character of engagement of the cover 90 to the glass neck of the receptacle also insures against fracture.

It is understood that the details of the construction may be varied, and I do not purpose limiting the patent granted on this application otherwise than necessitated by the prior art.

I claim:—

1. In a tumbling machine, a driving shaft, a driven shaft, a carrier comprising a frame fast at one end to the driven shaft, segmental clamping plates rigid with the ends of the frame projecting in one direction, segmental clamping plates disposed oppositely to the first plates, laterally projecting longitudinal shoulders upon the noncurved edges of the second plates provided with holes, clamping screws in the frame passing through the holes projecting above the shoulders, heads upon the screws, springs upon the screws with their ends pressing against the heads and the shoulders, and peripheral retaining flanges upon all the plates, and a container embraced by all the flanges.

2. A structure in accordance with claim 1 embodying a container and in which the driven shaft is provided with a groove in a vertical plane parallel with the plane passing through the receptacle mouth and the axis of the driven shaft, a partially rotatable locking member movable into and out of said groove to lock or release the collar from the driven shaft, and means for operating the locking member.

In testimony whereof I have affixed my signature.

ADOLF ENSSLIN.
